UNITED STATES PATENT OFFICE.

PETER V. BECKER, OF PLYMOUTH, WISCONSIN.

BRACKET FOR WAGON-BODIES.

SPECIFICATION forming part of Letters Patent No. 758,611, dated May 3, 1904.

Application filed February 13, 1904. Serial No. 193,383. (No model.)

To all whom it may concern:

Be it known that I, PETER V. BECKER, a citizen of the United States, residing at Plymouth, in the county of Sheboygan and State of Wisconsin, have invented certain new and useful Improvements in Brackets for Wagon-Bodies; and I do hereby declare that the following is a full, clear, and exact description of the same, reference being had to the annexed drawings, making a part of this specification, and to the letters of reference marked thereon.

The present invention has for its object to provide a device for securing to the bodies of wagons whereby the side sections thereof may be brought to any desired angle to a perpendicular to convert the body to various uses—such as a hay-rack, grain-rack, or to the many purposes for which a wagon-body may be found applicable—and this without the necessity of removing any rod, bolt, or other like fastenings.

The invention consists in a device adapted for attachment to the side sections of a wagon-body, constructed substantially as shown in the drawings and hereinafter described and claimed.

Figure 1 of the drawings is a perspective view of a portion of a wagon-body, showing my improved device connected to the side thereof; Fig. 2, a sectional elevation, on an enlarged scale, through a portion of the wagon-body, showing the device connected thereto, said device comprising two brackets, the lower one being shown in section and the upper bracket in elevation and also swung down at an angle in dotted lines; Fig. 3, a detail perspective view of the lower portion of the upper one of the brackets.

In the accompanying drawings the wagon-body is shown as comprised of the usual bottom A, the end-gate B, and the side sections C D E, which may be of any number desired; but in the present instance I have shown but three of these sections to illustrate the application of my invention thereto.

The device which constitutes my invention comprises two metal brackets F G, which may be of any suitable form and size and provided with any suitable means for attaching them to the side sections of the wagon-body, this being

left discretionary with the manufacturer. I have shown one of many means that may be successfully employed for securing the brackets to the side section of the wagon-body, which consists of the bolts *a* and the nuts *b*, engaging the screw-threaded end of said bolts, the bolts extending through the side sections and through the brackets. The lower bracket F is cast with or otherwise provided with a downwardly-extending bolt *c*, which extends through a cross-bar *d*, secured to the under side of the wagon-body, a nut *e* engaging the screw-threaded end of the bolt. The lower bracket F is always stationary, while the upper bracket G is movable and carries with it the side sections D E of the wagon-body to bring said sections to any angle from a perpendicular, as shown in dotted lines of Fig. 2 of the drawings. The lower side section E of the wagon-body is rigidly connected thereto, and, as previously stated, the bracket F, secured to said side section, remains a permanent fixture and stationary while in use. The bracket F has two wings *f* a certain distance apart, so as to form a space *g* between them to receive the lower end of the bracket G, which is connected to the wings by a stationary pivot-pin *h*, as shown in Figs. 1 and 2 of the drawings. The lower bracket F has a plurality of ratchet-teeth *i* and a lock device *j* to receive the rigid pawl device *k* and form a lock therefor when the side sections of the wagon-body are in an upright position, as shown in full lines of Fig. 2 of the drawings.

I do not wish to be understood as limiting my invention to any special construction of ratchet-teeth or to any number used, as any suitable ratchet device that will serve the purpose of holding the upper one of the brackets at the desired angle may be substituted for the means shown, although I consider the ratchet-teeth herein described the most practical.

In the present instance I have shown the lock device *j* as a simple socket, and when the pawl device *k* is engaged therewith the bracket G will be securely held in an upright position, as shown in full lines of Fig. 2 of the drawings.

The bracket G is pivotally connected to the bracket F through the medium of the stationary pivot-pin *h*, hereinbefore described,

an open slotted head *l*, cast with the upper bracket, engaging the pin and admitting of the bracket being raised the desired height to bring the same at the desired angle. The 5 lower end of the bracket *G* is located between the wings *f* of the lower bracket *F*, thereby holding the upper bracket in a true vertical line with relation to the lower bracket when the side sections of the wagon-body are in an 10 upright position, the wings also forming a guide for the upper bracket when brought down to the required angle to adapt the wagon-body to the uses desired. When it is desired to bring the sides of the wagon-body to an 15 angle from a perpendicular, the bracket *G* is raised a sufficient distance to disengage the pawl device *k* with the lock device *j*, when the bracket may be swung to the desired angle and held in its adjusted position by the pawl 20 device engaging the ratchet-teeth *i*, one position of the bracket being shown in dotted lines of Fig. 2 of the drawings.

Both the brackets *F* *G* may be of any suitable size and length to adapt them to wagon- 25 bodies of different heights, and two or more pairs of brackets may be used upon each side of the wagon-body, as found most desirable,

and many changes or modifications in the several details of construction may be resorted to without in any manner departing from the 30 essential features of the invention.

Having now fully described my invention, what I claim as new, and desire to secure by Letters Patent, is—

A device for attaching to the side sections 35 of a wagon-body, comprising a stationary bracket having a ratchet device, a lock device, and a stationary pivot-pin, and a movable bracket having a depending pawl to engage the ratchet device and the socket device when 40 the movable bracket is brought to an angle from a perpendicular or to an upright position respectively, said movable bracket having an open slotted head to engage the pivot-pin and enable the bracket to be raised to dis- 45 engage the pawl from the lock device, substantially as and for the purpose set forth.

In testimony whereof I affix my signature in presence of two witnesses.

PETER V. BECKER.
